(57) **CLAIM**

The ornamental design for an accent chair, as shown and described.

DESCRIPTION

FIG. 1 is a perspective view of an accent chair showing our new design.

FIG. 2 is a front view of an accent chair.

FIG. 3 is a rear view of an accent chair.

FIG. 4 is a left side view of an accent chair.

FIG. 5 is a right side view of an accent chair.

FIG. 6 is a top view of an accent chair; and,

FIG. 7 is a bottom view of an accent chair.

The broken lines in the drawings depict portions of the accent chair that form no part of the claimed design.
